(57) **CLAIM**

The ornamental design for a zipper tooth, as shown and described.

DESCRIPTION

FIG. 1 is a perspective view for a tooth of a zipper.
FIG. 2 is a front view of the design as seen in FIG. 1, the rear being a mirror image.

FIG. 3 is a side view of the design as seen in FIG. 1, the other side being a mirror image,

FIG. 4 is a top view of the design as seen in FIG. 1; and,
FIG. 5 is a bottom view of the design as seen in FIG. 1.
The broken lines shown throughout the drawings are for
illustrative purposes only and form no part of the claimed
design.
